ARTHUR C. CULVER AND ALBERT W. RUSSEL, OF DETROIT, MICHIGAN, ASSIGNEES TO
RUSSEL MOTOR AXLE COMPANY, OF DETROIT, MICHIGAN, A CORPORATION OF
MICHIGAN.

VEHICLE-BRAKE.

1,092,342.

Specification of Letters Patent.

Patented Apr. 7, 1914.

Application filed August 30, 1913. Serial No. 737,479.

To all whom it may concern:

Be it known that we, ARTHUR C. CULVER and ALBERT W. RUSSEL, citizens of the United States of America, residing at Detroit, in the county of Wayne and State of Michigan, have invented certain new and useful Improvements in Vehicle-Brakes, of which the following is a specification, reference being had therein to the accompanying drawings.

The invention relates to vehicle brakes of that type in which the brake-drum is mounted upon the wheel and the strap or shoe is mounted upon a non-rotating portion of the axle.

It is the object of the invention—first, to house and protect the strap or shoe, which engages the exterior of the brake-drum, and further, to hold said strap uniformly spaced from the drum when in released position so as to reduce the clearance required.

In the drawings: Figure 1 is a central section through the brake mechanism; Fig. 2 is a plan view thereof; and Fig. 3 is a side elevation.

A is an axle of any suitable construction; B is the brake-head mounted upon said axle; C is the wheel hub adjacent to the end of the axle and connected to the revoluble axle shaft D; and E is a brake-drum secured to the wheel C and projecting laterally therefrom.

Where it is desired to apply the brake both inside and outside the drum, an inner brake-shoe is used, and is operated by suitable mechanism, such as the rock shaft G. The outer brake is formed by a strap H which surrounds the drum and is operated by suitable lever mechanism I.

It is usual to provide an anchorage connection between the central portion of the brake strap and the brake-head, while the ends of the strap are connected with the lever mechanism. The anchorage connection is usually a laterally-extending bracket secured to the brake-head, and other brackets are provided for the fulcrums of the lever

connection. With our improved construction, in place of laterally-extending brackets, the brake-head B is provided with an integral flange J, which extends around the brake-strap and forms a housing therefor. This flange is provided with an inturned edge K, which is substantially in the center of the brake-strap, and is machined to be concentric with the axis of the wheel and drum. The diameter of the circle is also such as to provide clearance for the strap when released from contact with the drum, but this clearance is very small. It is nevertheless sufficient to hold all portions of the strap out of contact with the drum, and the true circular form of the flanges and its concentric relation to the drum will hold the strap also in concentric relation.

What we claim as our invention is:

1. The combination with a brake-drum, of a brake-head adjacent thereto, having a laterally-projecting flange with a circular edge portion concentric with the drum, and a brake-strap interposed between said flange and drum and held by the former in concentric relation when in released position.

2. The combination with a brake-drum, of a brake-head adjacent thereto, a flange projecting laterally from said head, embracing said drum and having an inturned edge portion machined concentric with the drum, and a brake-strap surrounding said drum and retained in its released position in concentric relation by bearing upon said machined edge.

3. The combination with an axle and a wheel, of a brake-drum mounted upon said wheel, a brake-head mounted upon said axle adjacent to said drum, an annular flange projecting laterally from said brake-head and provided with an inturned edge portion machined concentric with said drum, and a brake-strap embraced by said flange and supported in its released position by said machined edge with uniform clearance from the drum.

4. The combination with an axle and

wheel, of a brake-drum mounted on said wheel, a brake-head mounted on said axle, an internal brake mechanism for engaging said drum mounted on said brake-head, an external brake-strap and operating mechanism, also mounted on said head, and an annular flange projecting laterally from said head, embracing said brake-strap and provided with an inturned edge portion ma-

ched concentric with said drum and forming a seat for said strap in released position.

In testimony whereof we affix our signatures in presence of two witnesses.

ARTHUR C. CULVER.
ALBERT W. RUSSEL.
